UNITED STATES PATENT OFFICE.

RICHARD A. IRVING, OF GATESHEAD, ENGLAND.

SASH OPERATOR AND FASTENER.

Application filed March 26, 1924. Serial No. 701,966.

To all whom it may concern:

Be it known that I, RICHARD ATKINSON IRVING, a subject of the King of Great Britain and Ireland, residing at Gateshead, in the county of Durham, England, have invented certain new and useful Improvements in Sash Operators and Fasteners, of which the following is a specification, reference being had therein to the accompanying drawing.

This invention relates to sash operators and fasteners for windows and the like having vertically sliding sashes, and has for its object to provide improved devices whereby the upper sash can be lowered and raised by the movement of the lower sash and whereby the two sashes can be locked together either in the fully closed position or with one or both sashes partly open.

Devices in accordance with my invention comprise in combination a spring-pressed bolt of known type on the lower sash co-acting with a pair of special socket members on the upper sash disposed vertically one above the other. The bolt is capable of being fixed, when desired, in a position intermediate of its fully retracted and its fully projected positions. The upper of said special socket members has a rising track leading from below to the lower edge of the socket therein which lower edge is of such depth that it is cleared by the bolt in its intermediate position but is engaged by the bolt in its fully projected position, and the upper edge of said socket being of such depth that it is engaged by the bolt in its intermediate and in its fully projected positions. In use, when the lower sash is raised with the bolt in its fully projected position, the bolt rides up the rising track of the upper socket member and engages in the socket therein whereupon the upper sash can be lowered by pulling down the lower sash. When the upper sash has been lowered and it is desired to again raise it, the bolt is set in its intermediate position and the lower sash raised until the bolt coacts with the upper edge of the socket in the upper socket member, and the bolt then carries the upper sash up with the lower sash. When the lower sash is again pulled down, the bolt clears the lower edge of the socket and leaves the upper sash in its raised position. The lower socket on the upper sash is disposed so as to be in alignment with the bolt when the sashes are in the fully closed position,

the sashes being locked in this position by projecting the bolt into said socket. A supplementary socket is provided a short distance above the lower socket whereby the sashes may be locked when the lower sash is slightly raised or the upper sash is slightly lowered or when both sashes are slightly open, which supplementary socket may also be used to lower or raise the upper sash a short distance.

The accompanying drawings illustrate sash devices in accordance with my invention as applied to the sashes of a window. In the drawings, Figures 1 and 2 are elevations at right angles, only so much of the window sashes being shown as is necessary to illustrate the arrangement of my devices; Figures 3 and 4 are sectional elevations of the spring bolt in engagement with the upper socket and in engagement with the lowermost socket respectively; and Figure 5 is a section on the line X—Y in Fig. 4. Figure 6 is a similar view to Fig. 1 illustrating an additional fitting.

Referring to the drawings, I mount on the top bar 10 of the lower sash of the window a spring-pressed bolt 11 working in a barrel 12 containing a spring 13. The bolt has, at its rear end, two lateral projections 14, 15 which coact with the plug 16 closing the rear end of the barrel. The plug is slotted at 17 so that the bolt is free to slide therethrough only when said projections are in alignment with said slot. By retracting the bolt against the action of its spring and slightly rotating it, the projections are moved out of alignment with the slot, and the bolt can be temporarily fixed in the fully retracted position by engaging the projection 14 with the end of the plug, or in a position intermediate of the fully retracted and the fully projected positions by engaging the projection 15 with the end of the plug 16. A segmental track 18 in the end of the plug facilitates the rotary adjustment of the bolt 11. The operative end of the bolt is preferably provided with a small ball 19, and the rear end of the bolt is fitted with a knob 20 whereby it can be operated. The spring 13 within the barrel bears between a washer 21 bearing on a shoulder 22 around the bolt and the inner end of the plug 16.

To the face of one of the side bars 23 of the upper sash near the top thereof I attach an upper socket member 24 which is provided with a rising track 25 leading to

the lower edge of a socket 26, which lower edge is of less depth than the upper edge 27 thereof. One side of the socket member 24 is formed to suit the curvature of the 5 sash bar 23 to which it is attached by screws 28. The member 24 is also provided with a laterally-projecting finger piece 29.

At the bottom of the side bar 23 of the 10 upper sash I mount a lower socket member 30 having a socket 31 and preferably also a supplementary socket 32 to which lead rising tracks 33, 34 the distance between the 15 sockets 31 and 32 being chosen as that at which it is convenient to lock the sashes in a slightly open position. The depth of the lower edge of the socket 32 is less than that of its upper edge so that the bolt 11, when in its intermediate position, clears the lower edge of the socket 32.

20 In use, the upper socket member 24 is attached to the side bar 23 with its rising track 25 vertical as shown, and the lower socket member 30 is attached to the bar 23 vertically below the upper member 24 so 25 that its sockets 31, 32 are in vertical alignment with the socket 26. The bolt 11 is attached to the upper rail 10 of the lower sash so as to project horizontally in vertical alignment with the sockets 26, 31 and 32, the 30 socket 31 being in horizontal alignment with the bolt 11 when the sashes are closed.

When the bolt 11 is in its fully retracted position, as indicated in Fig. 4, the sashes are freely slideable. When the bolt is in its 35 intermediate projected position, as shown in Fig. 3, it clears the lower edges of the sockets 26 and 32 but engages the upper edges thereof. When the bolt is fully projected, as 40 shown in Fig. 1, it will engage and lock itself in any of the three sockets.

To operate the upper sash by means of the lower sash, if the upper sash is in its normal raised position and it is desired to lower it, the bolt 11 is set in its fully projected position after the sash has been raised to bring 45 the bolt above the socket 32, and the lower sash is then further raised until the bolt engages the socket 26, the bolt riding thereinto up the track 25. The lower sash is 50 then pulled down bringing the upper sash with it. If the upper sash has been lowered and it is desired to raise it, the bolt is set in its intermediate position and the lower sash raised until the bolt engages the upper edge 55 of the socket 26 when further raising of the lower sash raises the upper sash. The lower sash can be lowered again without affecting the upper sash, the bolt clearing the lower edge of the socket 26. The finger 60 piece 29 provides a means for raising or lowering the upper sash independently of the bolt 11. When it is desired to lower or raise the upper sash only a short distance, the socket 32 is used instead of the socket 26.

65 The sashes can be locked in the closed posi-

tion by projecting the bolt 11 into engagement with the socket 31 as shown in Fig. 1, or locked in a slightly open position by engaging the bolt with the socket 32.

While I have illustrated the bolt 11 and 70 socket members 24 and 30 as applied to the right hand side of a window it will be understood that they can be readily adapted for application to the left hand side of a window. Alternatively, the socket members may be attached to either side of the centre bar of the window, where such exists, and the bolt correspondingly disposed on the top bar of the lower sash. Where a window sash is provided with a horizontal cross bar 35, a bridge piece 36 having a double rising track 37 is mounted as shown in Fig. 6 on the side bar 23, or centre bar, in the vertical path of the bolt 11, said track engaging the operative end of the bolt and 85 guiding it over the cross bar.

What I claim as my invention and desire to secure by Letters Patent is:—

1. Sash operating devices for windows comprising the combination of a horizontally disposed barrel adapted to be mounted on the lower sash of the window, a spring-pressed bolt therein, and means for temporarily fixing said bolt in any one of three positions, namely a fully projected 90 position, an intermediate position and a fully retracted position, and a socket member, adapted to be mounted near the top of the upper sash of the window, said member having a socket which can be disposed 95 in vertical alignment with said bolt, the lower edge of said socket being of such depth that it is cleared by the bolt in its intermediate position but is engaged by the bolt in its fully projected position, and the 100 upper end of said socket being of such depth that it is engaged by the bolt in its intermediate and in its fully projected positions, and a rising track leading from below to 105 said lower edge.

2. Sash operating and locking devices for windows comprising the combination of a horizontally disposed barrel adapted to be mounted on the lower sash of the window, a spring-pressed bolt therein, and means for temporarily fixing said bolt in any one of three positions, namely a fully projected position, an intermediate position and a fully retracted position, a socket member adapted to be mounted near the top of the upper sash of the window, said member having a socket which can be disposed in vertical alignment with said bolt, the lower edge of said socket being of such depth that it is cleared by the bolt in its intermediate position but is engaged by the bolt in its fully projected position, and the upper edge of said socket being of such depth that it is engaged by the bolt in its intermediate 110 and in its fully projected positions, and a 115

rising track leading from below to said lower edge, and a second socket member adapted to be mounted at the bottom of the upper sash of the window, said member having a socket therein which can be disposed in vertical and horizontal alignment with the bolt when the sashes are in the closed position, and a supplementary socket disposed a short distance vertically above said lowermost socket, the lower edge of said supplementary socket being of such depth that it is cleared by the bolt in its inter-

mediate position but is engaged by the bolt in its fully projected position, and the upper edge of said supplementary socket being of 15 such depth that it is engaged by the bolt in its intermediate and in its fully projected positions, and said supplementary socket having rising tracks leading from above to its upper edge and from below to its lower 20 edge.

In testimony whereof, I affix my signature.

RICHARD A. IRVING.
